UNITED STATES PATENT OFFICE.

THOMAS LEDWARD, OF BROCKLEY, ENGLAND.

DESIGN FOR A CONDENSER-TUBE.

SPECIFICATION forming part of Design No. 24,439, dated June 25, 1895.

Application filed December 27, 1894. Serial No. 533,125. Term of patent 14 years. Patented in England September 24, 1891, No. 16,248.

To all whom it may concern:

Be it known that I, THOMAS LEDWARD, a subject of the Queen of Great Britain, and a resident of 9 Pendrell Road, Brockley, in the county of Kent, England, have invented a new and original Design for a Condenser-Tube, (patented in Great Britain, No. 16,248, dated September 24, 1891,) of which the following is a specification.

10 This design for a condenser tube is represented by the accompanying drawings, in which—

Figure 1 is a longitudinal elevation. Fig. 2 is a longitudinal section. Fig. 3 is a trans-
15 verse section through the line $x y$ of Fig. 2.

Similar letters of reference indicate corresponding parts in the several figures.

The design consists of a tube A with circumferential hollows B, B, and rims C, C, the rims having circumferential gills D, D projecting.

What I claim, and desire to secure by Letters Patent, is—

The design for a condenser tube as herein described and shown.

Signed at 35 Queen Victoria Street, London, England, this 10th day of December, 1894.

THOMAS LEDWARD.
